Attorney

UNITED STATES PATENT OFFICE

WILLIAM B. LOUDENSLAGER, OF ATLANTIC CITY, NEW JERSEY

NIPPLE FOR VITREOUS FLOATS

Application filed May 14, 1927. Serial No. 191,518.

This invention relates to improvements in nipples and it is an object of the invention to provide a device of this kind which is adapted to be held within a wall of vitreous or other material to provide means whereby a rod or other element may be readily and effectively coupled thereto.

Another object of the invention is to provide a device of this kind which, when in applied or working position, is effectively held against displacement and against turning or rotary movement independently of the wall or article to which it may be applied.

The invention consists in the details of construction and in the combination and arrangement of the several parts of my improved nipple whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view partly in section and partly in elevation illustrating a nipple constructed in accordance with an embodiment of my invention in applied or working position;

Figure 2 is a view in elevation of the inner end of my improved nipple as herein disclosed unapplied;

Figure 3 is a sectional view taken lengthwise through Figure 2;

Figure 4 is an elevational view looking at the smaller end of the nipple as herein disclosed.

As herein disclosed, my improved nipple comprises a tapered body portion 1 of desired dimensions and which has disposed inwardly thereof at its smaller end a threaded bore 2 in which is adapted to be engaged a rod or arm 3 or kindred member.

The larger end portion of the body 1 is provided therearound with an undercut shoulder 4 providing a head 5. This head 5 has disposed across its outer face, which is

flat, a relatively wide and deep groove or channel 6. The inner portion of the undercut shoulder 4 is defined by an outstanding annular member or plate 7 integrally formed with the body 1 and extending outwardly a material distance beyond the body 1 and the head 5. This plate 7, as herein disclosed, is circular in form.

As disclosed in the accompanying drawing, my improved nipple is shown as applied to a molded float, such as glass, of a type as embodied in Patent No. 1,465,370 dated August 21, 1923. This float F is molded and during the molding operation the vitreous material or the like employed is formed around the head 5 of the properly positioned nipple, resulting in the material snugly engaging inwardly of the tapered shoulder 4 and also within the groove or channel 6. Upon hardening of the material, the shoulder 4 provides means whereby the applied nipple is effectively held against displacement upon pull being imposed upon the nipple while the material within the groove or channel 6 effectively holds said applied nipple against turning or rotation.

It is also to be noted that the plate 7 has close contact with and is partially embedded within the outer surface of the wall of the molded article thereby materially strengthening that portion of the wall immediately adjacent to the applied nipple and at the same time withstand any stress which may be imposed upon the nipple.

From the foregoing description it is thought to be obvious that a nipple constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

A hollow vitreous body and a nipple designed to be engaged with the wall of said hollow vitreous body, comprising a body member having an undercut head, said head having a groove extending entirely there-across and open at both ends, the face of the head when in position being flush with the surface of the inside wall of the hollow body, the groove of the head receiving the vitreous material comprising the hollow body, the material in said groove being continuous with the inside wall of the hollow body at both ends of the groove for the purpose of preventing the nipple from turning when making a connection of another member with the hollow body, a relatively broad flange surrounding the nipple body adjacent the undercut head and embedded within the vitreous material for strengthening and supporting the material around the head, said nipple body member being provided with a socket to facilitate making a connection with said body.

In testimony whereof I hereunto affix my signature.

WILLIAM B. LOUDENSLAGER.
